UNITED STATES PATENT OFFICE.

GEORGE MARQUA, SR., OF NORWOOD, OHIO.

DESIGN FOR TOY AUTOMOBILE.

51,730.

Specification for Design.

Patented Feb. 5, 1918.

Application filed January 8, 1917. Serial No. 141,335. Term of patent 3½ years.

To all whom it may concern:

Be it known that I, GEORGE MARQUA, Sr., a citizen of the United States, residing at Norwood, in the county of Hamilton and State of Ohio, have invented a new, original, and ornamental Design for Toy Automobiles, of which the following is a specification, reference being had to the accompanying drawing, forming part thereof.

In the drawing:

The figure is a perspective view of a toy automobile representing my new design.

The part indicated by dotted lines on the

drawing represents one form of support or mounting for my design, but obviously the design could be mounted or used in connection with any other suitable support or mounting.

I claim:

The ornamental design for a toy automobile, substantially as shown and described.

GEORGE MARQUA, SR.
